CHAIN LADDER

Harold P. Hopp, Englewood, N. J., and Edward Kunzelman, Mount Vernon, N. Y., assigns to H. K. Metal Craft Manufacturing Co., New York, N. Y.

Application December 22, 1942, Serial No. 469,793

4 Claims. (Cl. 228—40)

This invention relates to new and useful improvements in flexible ladders and more particularly it pertains to a novel construction for connecting rigid rungs to flexible stiles in ladders of the flexible type.

It is one object of the invention to provide a novel rigid connection between a rigid ladder rung and a flexible ladder stile.

It is a further object of the invention to provide a novel construction which in addition to forming means for attachment of ladder rungs to ladder stiles, provides means for reinforcing the ladder rungs.

It is a still further object of the invention to provide a rung and stile connection which is simple in construction and easy of assembly.

In the present embodiment, stiles in the form of chains of the so-called lock link type have been illustrated, but it is to be understood that other types of flexible stiles may be employed without departing from the spirit of the invention.

With the above and other objects in view, reference will be had to the accompanying drawing, the following specification and the claims.

In the drawing,

Figure 1 is a view in elevation partly broken away and partly in section illustrating a section of a flexible ladder constructed in accordance with the present invention.

Figure 2 is a view in elevation partly broken away and taken at right angles to Figure 1.

Figure 3 is a detail sectional view on an enlarged scale taken substantially on the line 3—3 of Figure 1.

Figure 4 is a detail sectional view on an enlarged scale taken substantially on the line 4—4 of Figure 2, and

Figure 5 is a detail sectional view on an enlarged scale taken substantially on the line 5—5 of Figure 1.

Referring specifically to the drawing, the stiles of the ladder are designated 10, the rungs being designated 11.

The stiles 10 are formed from chain preferably of the so-called lock link type and consequently are of a flexible character.

The rungs 11 are of hollow construction being formed of sheet metal, are preferably substantially square in cross-sectional shape and have open ends.

Upon its tread surface 12, each rung is provided with two raised beads 13 which extend longitudinally thereof, there being one at each side of the tread surface as best illustrated in Figure 5 of the drawing.

That wall of the rung which is opposed to the tread is formed of two sections 14 and 15 which are integral extensions of their respective side walls of the rung and each is formed with an inwardly turned flange 16. These flanges meet in the completion of the rungs as illustrated in Figure 3 of the drawing.

As best illustrated in Figures 4 and 5 of the drawing, this last mentioned wall of the rung is cut out or notched at its ends as at 17, the purpose of which will be hereinafter specifically pointed out.

The rungs 11 are rigidly attached to the stiles 10 with the rungs in spaced relation to one another and the means by which this is accomplished will now be described.

The reference characters 18 and 19 designate two U-shaped clips and as best illustrated in Figure 3, the clip 18 is nested within the clip 19.

In each of its leg portions, the clip 18 is formed with two openings 20, so positioned that each opening in one leg is directly opposite to one of the openings in the other leg. Each of these openings is so formed as to provide a slight inwardly extending flange or shoulder 21 which extends entirely around the opening.

Each of the leg portions of the clip 19 is provided with two openings 22 which are so positioned in the leg portions of the clip as to register with the openings 20 in the leg portions of the clip 18 when the clips are properly nested.

The base portion of the clip 18 is formed with two spaced inwardly depressed channels 25 which receive the legs 26 of one of the links of the stile 10 as best illustrated in Figure 3 of the drawing.

The legs 26 of the stile link are retained in their respective channels by the base portion 27 of the clip 19 when the clips are nested together and the clips are secured together by means of a rivet 28 which passes through the base portions 25 of the clips at a point between the legs of the link.

Rigid bracing means is provided for the rung and the leg portions of the clips 18 and 19 and such means is herein illustrated as tubular members 30.

These bracing members 30 are positioned between the leg portions of the inner clip 18, see Figure 3 of the drawing, with their open ends receiving their respective flanges or shoulders 21 which serve to support the members 30 in position during assembly of the structure.

Openings 31 are formed in the side walls of the rung 11 and these openings are so located as to register with the openings 22 of the clip 19, the

openings 20 in the clip 18, and the passages of the tubular bracing members 30 when the nested clips are inserted into position in the open end of the rung.

The structure is assembled in the following manner.

The proper link of the stile having been determined, its side legs 26 are placed in the channels 25 in the base portion of the clip 18 after which the clip 18 is nested within the clip 19 and the 10 clips are secured together by the rivet 28.

In securing the link between the base portions of the clips 18 and 19, the loop portion only of the link is engaged by the clips and as illustrated in Figure 5 of the drawing, the base portion of the clip 18 is cut out as at 34 to accommodate the 15 lock portion 35 of the link.

After the clips have been secured to the stile link, the leg portions thereof are slightly spread to permit of placement of the tubular bracing members 30 upon their supporting flanges or shoulders 21.

The clips are next inserted into the end of the rung to a position in which the registered openings 20 and 22 in the leg portions thereof register with their respective openings 31 in the side walls of the rung. In this position, the lock of the 20 link passes into the cut out portion 17 in the end of the bottom wall of the rung as illustrated in Figure 4.

With the parts in this position, rivets 36 are passed through the registered openings 31, 20 and 21, and the tubular bracing members 30 and upset to secure the parts together as a rigid structure.

In setting the rivets 36, the side walls of the rung and the leg portions of the clips 18 and 19 are firmly clamped between the heads of the rivets and their respective ends of the tubular bracing members 30.

The members 30 perform two functions as follows.

First, they prevent inward collapsing or bending of the leg portions of the clips, and the side walls of the rung at the end thereof, and secondly, they prevent bending of the rivets 36.

As illustrated in the drawing, the U-shaped clips 18 and 19 are so proportioned as to fit snugly within the rung thus making for a rigid connection when the several parts have been secured together.

While in the foregoing, we have described but one means for attaching the rung to one stile, it will be understood that the opposite end of the rung is attached to its stile by the same structure.

Having thus described the invention, what is claimed as new is:

1. In a flexible ladder in combination, stiles, a

hollow rung having open ends and means for attaching each end of the rung to its respective stile, said means comprising a pair of nested U-shaped clips adapted for insertion into each of the open ends of the rung, means for securing each pair of nested clips to its respective stile, means bridging the rung transversely thereof for securing each pair of nested clips to the rung, and means interposed between the nested clips for maintaining them in spaced relation.

2. In a chain ladder in combination, a pair of spaced chain stiles, a hollow rung of rectangular cross-sectional form having open ends and means for attaching each end of the rung to its respective stile, said means comprising a pair of nested U-shaped clips adapted for insertion into each of the open ends of the rung with the legs of the outer clip in engagement with opposite side walls thereof, rigid bracing means disposed between the legs of the nested clips for maintaining them in spaced relation, means for securing each pair of nested clips to its respective stile, and means passing through the side walls of the rung and the legs of the nested clips for securing the clips to the rungs.

3. In a flexible ladder in combination, a pair of spaced stiles, a hollow rung having open ends, and means for attaching each end of the rung to its respective stile, said means comprising a pair of nested U-shaped clips adapted for insertion into each of the open ends of the rung, means for attaching each pair of nested clips to its respective stile, rigid tubular bracing means disposed between the legs of the nested clips to maintain them in spaced relation, and means passing through the side walls of the rung, the legs of the nested clips and the rigid tubular bracing means for securing the clips to the side walls of the rungs.

4. In a chain ladder in combination, chain stiles, a hollow rung having open ends, and means for attaching each end of the rung to its respective stile, said means comprising a pair of nested U-shaped clips adapted for insertion into each of the open ends of the rung, means for attaching each of said pairs of nested clips to its respective stile with a link of the stile disposed between the bases of the nested clips, rigid tubular bracing means disposed between the legs of the nested clips for maintaining them in spaced relation, means for supporting said rigid tubular bracing means in position between the legs of the clips, and means extending through the rigid tubular bracing means, the legs of the nested clips and the side walls of the rung for securing the nested clips in the open ends of the rung.

HAROLD P. HOPP.
EDWARD KUNZELMAN.
